UNITED STATES PATENT OFFICE.

FREDERICK WEYHRAUCH, OF NEW YORK, N. Y.

BRUSH CLEANER.

1,425,923.

Specification of Letters Patent. Patented Aug. 15, 1922.

Application filed April 19, 1921. Serial No. 462,492.

To all whom it may concern:

Be it known that I, FREDERICK WEYHRAUCH, a citizen of the United States, residing at New York city, in the county of New York and State of New York, have invented certain new and useful Improvements in Brush Cleaners, of which the following is a specification.

My invention relates to improvements in brush cleaners for use primarily in cleaning rotary brushes such as are used in carpet sweepers, vacuum cleaners and the like and it is my object to produce a cleaner which may be cheaply manufactured, efficient and capable of use by anyone.

In the drawing Fig. 1 is a perspective view of my improved cleaner and Fig. 2 a sectional view of the structure of Fig. 1 on the line 2—2 thereof.

The cleaner comprises a handle 1 and a comb 2, preferably at right angles to the handle. For cheapness in production this may be stamped out of sheet metal.

The end tooth 3 of the comb has a laterally extending projection 4 in the plane of the teeth and it, together with the outer edge of the tooth from which it projects, is provided with a cutting edge.

As is well known rotary brushes, such as are used in carpet sweepers, vacuum cleaners and the like, pick up threads, lint, ravelings and hairs which become tightly

wound around the brush and core to such an extent that the bristles are bound down and the brush will not perform its functions.

When a brush has reached this condition it can be quickly and easily cleaned by the use of my device.

The cutting edge of the comb is pulled longitudinally between the rows of bristles whereby the wound-up threads, ravelings, etc., are cut, the advanced cutting edge on the projection 4 getting under the windings and cutting them instead of riding over them as would be the case if the cutting edge were not advanced at the point. After the windings have been cut the comb is pulled through the bristles removing the cut windings and straightening out the bristles. As the cutting edge is at right angles to the line of motion when combing the bristles are not injured.

I claim:

A brush cleaner comprising a handle, a comb depending therefrom, one end tooth of which is provided with a laterally extending projection in the plane of the teeth, said projection and outside edge of the tooth being provided with a cutting edge.

In testimony whereof I have affixed my signature.

FREDERICK WEYHRAUCH.
